To all whom it may concern:

Be it known that I, Abraham N. Spanel, a citizen of the United States and a resident of New York, New York, whose post-office address is 1100 Park Avenue, in the city, county, and State of New York, have invented a new, original, and ornamental design for a Panty Girdle, of which the following is a specification, reference being had to the accompanying drawing, forming part thereof, wherein:

Figure 1 is a front view; and

Fig. 2 is a rear view of a panty girdle showing my new design.

The characteristic feature of my design resides in the combination, on the panty girdle disclosed, of the perforations arranged thereon as shown.

I claim:

The ornamental design for a panty girdle, substantially as shown and described.
